SPENCER W. STEWART, OF WHITE PLAINS, NEW YORK, ASSIGNEE TO AMBURSEN CONSTRUCTION CO., INC., OF NEW YORK, N. Y., A CORPORATION OF NEW YORK

SUBTERRANEous MASONRY STRUCTURE AND METHOD OF MAKING THE SAME

Application filed April 30, 1930. Serial No. 442,453.

This invention relates to a novel and improved method of excavating and is particularly applicable where an excavation has to be carried down through material of such 5 character that it is difficult to maintain the sides of the excavation and prevent them from caving in. The invention also includes the structure placed in the excavation. In the past it has been customary to employ 10 expensive bracing caisson work and there have been times when no caisson work would retain the sides of the excavation. One of the objects of my invention is therefore to devise a method which is relatively inexpensive as compared to prior art practice and 15 which may be used with substantially all known materials through which excavation has to be carried.

A further object of my invention is to 20 provide a method by means of which water draining into the excavation may be handled in an expeditious way without interfering with the work of excavating and the work of placing the foundation.

25 The invention also contemplates a way in which grouting may be conveniently combined with other features of the invention.

While I have named above some of the 30 principal objects of the invention, it is to be understood that these are not exhaustive, as other objects will be apparent to those skilled in the art from a study of the following description when read in connection with the accompanying drawings, in which I 35 have shown the way in which my invention may be practiced with one type of structure and in which

Fig. 1 is a longitudinal vertical section through a cut-off wall of a dam showing how 40 my invention may be practiced in connection with the excavation for, and the building of, this wall.

Fig. 2 is a section taken at right angles to that of Fig. 1 and further illustrating the 45 possibilities of my invention.

Fig. 3 is a top plan view of a portion of a cut-off wall excavation in progress of being made.

Fig. 4 is a cross section through a dam having a cut-off wall completed.

Fig. 5 is a vertical section through a subterraneous wall showing another way in which the invention can be practiced, and taken on the line 5-5 of Fig. 6.

Fig. 6 is a section on the line 6-6 of 55 Fig. 5.

This invention may be employed in any place where it is desired to place masonry in the ground, but for purposes of illustration only I have shown, and shall describe, a 60 cut-off wall of a dam, it being understood that the steps described in connection with the building of such a wall may be equally well practiced with any other kind of structure involving work of this type and which is 65 generally termed foundation work.

Referring now to the drawings and particularly to Fig. 1, I have shown therein a profile of a dam site and more particularly the parts thereof where the cut-off wall is to 70 be placed. At the opposite ends of this figure the lines 1 indicate the surface to which excavation has been made and upon which the curtain wall has been placed, these portions supplying suitable material to support 75 the wall. The dash line 2 at the bottom of the figure indicates the continuation of the lines 1, or, in other words, the surface to which excavation is to be made and the full line 3 above the line 2 indicates the surface 80 to which excavation has been made at the time which we are now considering.

In carrying on excavation for a structure of this type, and according to my invention, I first carry a portion of the excavation to a 85 convenient depth, such as that indicated by the line 4 in Fig. 2. The depth of this excavation will ordinarily be such that either no bracing at all is required or only slight bracing. The depth will of course depend upon 90 the class of material being excavated. Preferably this excavation is over a limited part of the total area to be excavated. For example, looking at Fig. 3, the area on which excavation is started may comprise that indicated at 5, or, if desired, a greater area, such as that indicated at 6. The excavation may be carried on simultaneously at several 95 sections, preferably spaced along the length of the area to be excavated.

As best shown in Fig. 2, the sides of the excavation are preferably tapered or wedge-shaped, as indicated at 7. After the excavation has been carried to a depth such that the continued maintenance of the sides becomes difficult, work on the excavating is suspended and concrete or other masonry is placed in the excavation, suitable forms being used to maintain a shaft the sides of which are indicated at 8. The masonry 9 is poured between the forms and the walls of the excavation or the walls formed by adjoining sections of masonry in case other sections have been filled hitherto. In the masonry is placed reinforcing 10 in the form of vertically extending rods having hooks 11 at their lower ends. In placing the concrete preferably I follow the practice indicated in Fig. 1 of placing at the bottom of the excavation a quantity of easily removable material 12 upon which the concrete is placed and into which the hooks 11 may be easily forced. After the concrete or other masonry has become set, the work may continue by further excavation at the bottom 25 of the shaft, the excavation starting, of course, with the removal of the previously placed material 12, and after this material is removed the excavation proceeds until once more it becomes difficult to maintain the walls from caving in and then another section 13 of masonry is put in place, still maintaining a shaft through the center of the masonry. This second section also carries reinforcing 10 and the rods forming this reinforcing are preferably secured to the reinforcing in the section above and this may be conveniently done by having hooks which engage the depending hooks 11. With this arrangement the reinforcing helps to support the lower section, although the walls of the excavation are preferably also flared, as shown in Fig. 2, so as to provide a wedging action by means of which the section is supported from the walls of the excavation, even without help from the reinforcing. In like manner each section is put in place beneath the section above it and finds a support on the walls of the excavation and it will be obvious that very little, if any, bracing is required. The amount of bracing will of course depend upon the nature of the material being excavated, but the total amount is negligible compared to what would be necessary in carrying the excavation down 55 to its full depth before placing masonry therein, as is the common practice to-day.

After one shaft has been carried down to the bottom of the finished excavation, the shaft may be filled with concrete, if desired, thus presenting a solid, substantially monolithic structure.

The above method may be followed next by excavating other sections, for example, those between sections already excavated and concreted, the adjoining sections being pref-

erably tied together by suitable joints 14, as shown in Fig. 1.

The above method and the resulting wall or other structure have many advantages which will be apparent to those skilled in the art. For example, in excavating under present practice it is often the case that the complete excavation cannot be made and the masonry placed between times of maximum flood flows. Consequently the excavation is flooded before completion of the structure and this involves costly pumping and often-times serious damage to the structure. By the practice of my invention the excavation is made and the structure in the excavation completed almost simultaneously, with the exception of the shafts and even if a shaft itself is flooded the walls of the excavation are protected and by proper arrangement of schedules it would usually be possible to complete certain sections of the finished structure between times of flood so as to minimize the amount of pumping necessary. If a shaft is not filled before flood-time, it may be temporarily plugged or otherwise covered until the flood recedes.

Another feature of importance is the handling of water during excavation and concreting. The shaft furnishes a convenient means for running to the bottom of the excavation a pipe 15 by means of which a pump 16 may remove the water from the bottom of the shaft while work is progressing.

In excavating water bearing material is often encountered and this produces hydrostatic pressure on the side walls or bracing, if such be used. According to my invention, however, the concrete when put in place may be provided with suitable reinforcing sufficient to take care of any stress which may be placed upon it and this stress may be greatly reduced by means of branch drainage pipes 17 connected to the pipe 15, as best shown in Fig. 1. As shown in Fig. 2, water from a water bearing plane of cleavage 18 may be drained into a box 19 and thus carried through the pipe 15 to the surface. These pipes 17 may also collect water from all other points where there is water bearing material and of course the pipe 15 removes the water from the bottom of the excavation, in which is provided a sump 20 to which all water reaching the bottom of the excavation is carried.

It will be noted from the above arrangement that the cost of pumping is reduced to a minimum. Instead of following the usual practice of carrying all water from the excavation to the bottom and there collecting it in the sump and pumping it to the top, according to my invention the water is pumped to the top substantially from the place where it is found, thus avoiding the necessity of lifting it all from the bottom. The difference in pumping head is substan-

tial, particularly in an excavation of any great depth.

As the work progresses there is apt to be slight settlement which will leave small openings between the different sections. There will also be a slight shrinkage away from the walls of the excavation and there will be spaces left between the masonry and the tops of pockets of soft material which may be excavated. These spaces may be conveniently filled by using the lateral pipes 17 for grouting, after the excavation is completed and before the shaft is filled. In fact, if necessary, the pipe system may be left entirely in place and used for pumping, if desired, if not used for grouting. In other words, the arrangement is a flexible one lending itself to use to meet the varying conditions which are of course always arising in work of this character.

Another feature of importance in connection with my invention is the fact that in making an excavation if pockets of soft material, as indicated at 21, are reached it is possible to extend the excavation sidewise to a place where proper bearing material is obtained. Under present practice it is necessary to break through the sides of the sheeting or other protection and excavating this material with not only great difficulty, but oftentimes great danger to the workman and to the structure itself. This difficulty and danger is increased if the soft material is also water bearing.

By providing the easily removable material 12 beneath a section which is being completed it is possible for a workman to very quickly obtain a suitable working space at the bottom of a shaft. The dimensions of a shaft or well under some conditions might make the attainment of an easy working space below it very difficult without the provision of this material.

In Fig. 1 I have indicated two sections at the left of this figure as corresponding to the sections 9 and 13 of Fig. 2, and I have also indicated lines 4 separating not only these sections, but other sections in the finished shafts. The work may be carried on as shown in Fig. 3 in sections, each containing one shaft or a plurality of shafts, all as may be found most expedient for the particular job.

While, as stated above, the invention may be used in connection with any subterraneous work, it has been found particularly adapted for use in building cut-off walls for dams and in Fig. 4 I have indicated a dam 22 having on its upstream side a cut-off wall 23 connected to the dam by a slab 24 of concrete extending upstream from the dam.

In the form shown this dam is of the well known Ambursen type, although the invention, of course, may be used with other types of dam.

While under normal conditions the shafts after completion will be filled with concrete or other masonry to form a substantial monolithic structure, nevertheless if found desirable one or more shafts may be left permanently open so as to provide access to certain parts of the interior of the foundation. This again will of course depend upon the conditions surrounding each particular job.

In the above description I have set forth one way in which the invention may be used to build a cut-off wall, and now I shall describe a way in which a similar structure may be built by another method employing the principles of the invention. This method is illustrated in Figs. 5 and 6, and referring thereto, I have indicated at 25 a river beneath whose bed it is desired to build a cut-off wall. It often happens in such situations that it is difficult if not impossible to build a cut-off wall by ordinary methods or by working downwardly from the bed of the river. Again, it may be desired to deepen a cut-off wall already in place. In either of the above situations my invention finds utility, as well as in others which will be apparent to those skilled in the art.

Assuming the line 26 to represent the profile to which excavation is to be carried, and that it is impracticable to unwater the site, I may proceed by sinking shafts at 27 and 28 on opposite banks of the stream. These shafts may be carried down in the usual manner or in the way described above. In order to illustrate the several ways in which the invention may be used, I have shown the shaft 27 as being excavated to the full depth of the profile, while the shaft 28 is shown as being carried down only a relatively short distance.

If two shafts are used, adits are run under the river until they meet to form a continuous tunnel from one shaft to the other. The walls of this tunnel are sloped as shown in Fig. 5, and the tunnel is then filled with concrete, which will be supported from the walls of the tunnel, as shown at 29 in Fig. 6. Then we have one horizontal layer 30 of the wall in place. The next step is to work inwardly from the shafts along this layer, and this may be done on both the top and bottom of the layer. In Fig. 5, I have shown a second adit or tunnel 31 completed beneath the layer 30, and ready to receive the concrete, while another layer 32 has been already placed above the layer 30, and other adits 33 and 34 are shown as started in from the shafts 27 and 28, respectively. The work may be continued in this way, working both up and down from the first layer and building other layers which may be independently supported from the sides of the excavation as they are built, until the entire wall is completed. Suitable joints 35 may be provided between adjacent layers, these being shown as over-

lapping projections, although other forms such as reinforcing may be used, for example, as shown in Fig. 2. Each layer is supported from the sides of the adit in which it is placed.

5 A similar procedure may be followed using only one shaft. When this is done, an adit is run laterally from a shaft and filled with concrete to form a layer of the wall, as indicated at 36. This adit illustrates one 10 advantage of this invention, which is that the excavation may conveniently be made to follow a pocket or seam of poor material, in this case this pocket being indicated at 37. In connection with this layer I have shown 15 another feature which may be used with any and all layers of the wall, and that is the use of grouting pipes 38, which may be used in the first instance for drain pipes and then to grout the joints between the wall layers.

20 Beneath the layer 36 I have shown a second layer 39 in place and keyed to the layer 36, and adits 40 and 41 above and below these two layers, these adits being shown as in the course of being excavated. These adits, as 25 well as all others referred to herein, may be excavated by broaching or by other known methods, and each layer of the wall which fills an adit after it is constructed is likewise supported from the sides of the adit. In the 30 adit 41 I have shown drain pipes connected to a vertical pipe 42 provided with a pump 43 for forcing water to the top. After these pipes have served their purpose as drains, 35 they may be used as grout pipes, as described above.

Thus it will be seen that a wall may be built by working from several different levels, either from one shaft or a plurality of shafts.

40 If desired, the shaft may be excavated to the full depth of the wall and then an adit dug and filled with concrete on the bottom of the profile, as shown at 44. The wall may then be built upwardly by the excavation and 45 filling of successive adits. Here I have shown reinforcing rods 45 provided with hooks to engage hooks on rods in adjoining layers in order to tie them together, and it is to be understood that a similar arrangement may be used between all adjoining layers where desirable. Here too I have shown a pipe 38 which may be used in this instance as a grout pipe only, being provided with short branches 38' extending to the joint between layers. 50 Similar branches are of course used with the other pipes 38 after they have ceased to be used as drains and are to be used for grouting. A sump 46 may be maintained at the bottom of the shaft as the work progresses.

60 A subterraneous structure may be built according to this invention with relative ease as compared to prior methods, and in building it difficulties may be more easily overcome as they arise. For example, as noted 65 above, soft pockets or seams may be followed

and excavated as far as may be necessary. Often soluble material is encountered, and by this method such material which has caused failures of dams, may be removed. The work may be carried on simultaneously 70 from different levels, if desirable, thus greatly expediting procedure.

While the material may be removed from the shafts in any manner, I have illustrated 75 buckets 47 for lifting the material, it being understood that these are merely exemplary of any suitable hoisting apparatus.

I claim:

1. The method of excavating, which comprises removing material to form an excavation, placing in the bottom of the excavation easily removable material, building in the excavation a section of a shaft with its bottom disposed adjacent said easily removable material, supporting said section from the walls 80 of the excavation, removing said easily removable material through said shaft, excavating further material beneath said section and placing another section of the shaft in the excavation beneath said first section. 85

2. The method of building a subterraneous structure which comprises forming an excavation, filling the excavation with masonry in wedge form, supporting the masonry by its wedge action against the walls of the excavation, excavating beneath said masonry, 90 and depositing more masonry in the excavation beneath the first masonry. 95

3. The method of building a subterraneous structure which comprises forming an excavation wider at its top than at its bottom, 100 filling the excavation with masonry to form a horizontal layer of the structure, forming a second excavation beneath said layer, and depositing a second layer in said second excavation. 105

4. The method of building a subterraneous structure which comprises sinking a shaft, excavating an adit running from said shaft, with the top of the adit wider than its bottom, filling said adit with masonry to form a horizontal layer of said structure, excavating a second adit beneath the first one, and inserting masonry in said second adit. 110

5. The method of building a subterraneous structure which comprises sinking a shaft, excavating an adit running from said shaft, with the top of the adit wider than its bottom, filling said adit with masonry to form a horizontal layer of said structure, excavating other adits of similar form above and below said first adit, and filling said other adits with masonry to form other layers of the structure. 115

6. The method of building a subterraneous structure which comprises sinking a shaft, running adits from said shaft at a plurality of levels, with each adit wider at its top than at its bottom, filling said adits to form spaced layers of the structure, and closing the spaces 120 125 130

between said layers by excavating and filling successive adits, beginning at said layers.

7. A subterraneous masonry structure comprising a plurality of contacting sections one beneath the other, with the top of each section extending outwardly further than the bottom of the superjacent section and further than the bottom of the same section and in contact with the material adjoining the superstructure.

8. A subterraneous masonry structure comprising a plurality of sections one beneath the other, with a portion of each section above its bottom extending outwardly into the material adjacent the structure a distance further than said bottom and further than the bottom of the superjacent section to form a wedge contacting with said material.

9. A subterraneous masonry structure comprising a plurality of sections one beneath the other, with a portion of each section above its bottom extending outwardly into the material adjacent the structure a distance further than said bottom and further than the bottom of the superjacent section to form a wedge contacting with said material, said sections having a shaft running vertically therethrough.

10. A subterraneous masonry structure comprising a plurality of sections one beneath the other, with a portion of each section above its bottom extending outwardly into the material adjacent the structure a distance further than said bottom and further than the bottom of the superjacent section to form a wedge contacting with said material, said sections having a shaft running vertically therethrough and filled with masonry.

11. The method of building a subterraneous structure, which comprises forming an excavation, filling the excavation with masonry in wedge form, supporting the masonry by its wedge action against the walls of the excavation, excavating beneath said masonry and outwardly beyond the bottom thereof to form a wedge-shaped excavation, and depositing more masonry in said wedge-shaped excavation.
